Attorney

UNITED STATES PATENT OFFICE.

MERL H. HARTMAN, OF ELMINS, WEST VIRGINIA.

WRENCH.

No. 867,504.

Specification of Letters Patent.

Patented Oct. 1, 1907.

Application filed April 1, 1907. Serial No. 365,790.

To all whom it may concern:

Be it known that I, MERL H. HARTMAN, a citizen of the United States, residing at Elkins, in the county of Randolph and State of West Virginia, have invented 5 certain new and useful Improvements in Wrenches, of which the following is a specification, reference being had therein to the accompanying drawing.

My invention relates to improvements in monkey wrenches of that type in which the movable jaw may 10 be quickly adjusted.

The object of the invention is to provide a device of this character which will be of simple, strong, durable and comparatively inexpensive construction and which may be quickly and easily adjusted.

15 Further objects and advantages of the invention, as well as the structural features by means of which these objects are attained, will be made clear by an examination of the following specification, taken in connection with the accompanying drawings, in which,

20 Figure 1 is a side elevation of my improved monkey wrench; Fig. 2 is an edge view of the same; Fig. 3 is a longitudinal section through the wrench, showing in full lines its movable jaw in its locked position and in dotted lines said jaw in its released position; Fig. 4 is 25 an elevation of the inner edge of the movable jaw; Figs. 5 and 6 are cross sections taken respectively on the planes indicated by the lines 5—5 and 6—6 in Fig. 3; and Fig. 7 is a view similar to Fig. 6, but showing the 30 position of the parts when the movable jaw of the wrench is released or unlocked.

Referring to the drawings by numeral 1 denotes the shank or body portion of the wrench, the upper part of which is rectangular in cross section and has formed upon it the stationary jaw 2 of the wrench. The co- 35 acting movable jaw 3 is adapted to slide longitudinally on the rectangular portion of the shank 1 and is also adapted to have a slight swinging movement thereon. This swinging movement is permitted by flaring the opening 4 in the jaw 3 through which the shank 1 projects and slides.

Depending from the bottom of the jaw 3 is an integral stem or shank 5 provided with a flat, inner face to slidably engage the flat inner face 6 of the shank 1. The shank 5 is formed in its inner face with a longitudinally 45 extending groove 7 and with a series of transversely extending ratchet teeth 8. The latter are adapted to be engaged by one or more ratchet teeth 9 formed upon the flat inner face 6 of the shank 1.

The lower end of the shank 1 is reduced and of substantially semicircular shape in cross section, as shown at 10 in Fig. 6, and beneath said portion 10 is a laterally offset cylindrical portion 10^a adapted to serve as a bearing for the handle as hereinafter explained; and the extreme lower end of said shank is formed with a 55 reduced threaded portion 11.

The shank 5 is similar in shape to that of the portion

10 of the shank 1, so that the lower ends of both of the shanks may be telescoped by a handle 12 formed with a cylindrical bore 13.

The diameter of the upper portion of the bore 13, as 60 shown in Fig. 6, is equal to the combined thickness of the lower ends of the shanks 1 and 5, so that said shanks will be held in contact with each other and with the ratchet teeth 8, 9, in engagement and the movable jaw will be thus locked upon the shank of the stationary jaw. The lower portion of the bore 13 is reduced 65 to receive the cylindrical bearing portion 10^a of the shank 1 and to thereby give the handle a firm bearing so that it cannot tilt laterally or transversely.

To enable the ratchet teeth 8 on the shank of the 70 movable jaw to be disengaged from the teeth 9 on the shank 1, a cavity or recess 14 is formed in one side of the bore 13, so that when the handle is turned upon the shanks to its position shown in Fig. 7, the lower end of the shank 5 will swing outwardly into said recess 75 14, thereby disengaging the ratchet teeth so as to enable the jaw 3 to be moved longitudinally on the shank 1. The shank 5 is moved outwardly by a leaf spring 15, which has one of its ends secured at 16 in the lower portion of the shank 1 and its other end projecting into 80 the longitudinal groove 7 in the shank 5.

A stationary collar or sleeve 17 is provided upon the shanks 1 and 5 between the upper end of the handle and a shoulder 18 formed by reducing the lower end of the shank 1. This collar 17 fits the reduced rectangular portion of said shank and its opening 19 through which both of the shanks project is of sufficient width to allow for the swinging movement of the shank 5. The sleeve 17 and handle 12 are retained upon the shanks by a nut 20 engaged with the threaded end 11 90 of the shank 1, as clearly shown in Fig. 3. In order to readily indicate the two positions to which the handle must be turned to lock and release the movable jaw 3, I preferably form on the stationary sleeve 17 marks or scores 21, 22, and upon the handle 12, an arrow or 95 score 23 which is moved into alignment with the points 21, 22.

The construction, operation and advantages of the invention will be readily understood upon reference to the drawings. It will be seen that when the movable jaw 3 is locked the arrow 23 alines with the point 22 and the shanks 1 and 5 are held in contact with each other owing to their engagement with the walls of the opening or bore 13 in the handle 12. When the shanks are in this position the ratchet teeth 8 and 9 mesh 105 with each other and effectively hold the jaw 3 against longitudinal movement. When it is desired to release the jaw 3 so that it may be adjusted longitudinally on the shank 1, the handle 12 is given a quarter turn and its arrow 23 caused to aline with the point 21. This 110 position of the parts is indicated in dotted lines in Fig. 3 and in full lines in Fig. 7. When the handle 12 is

thus turned, the spring 15 forces the shank 5 away from the shank 1 and into the cavity or recess 14 in the handle, thus disengaging the ratchet teeth 8 from the teeth 9. When these teeth are disengaged the jaw 3 5 may be quickly adjusted longitudinally to fit a nut, bolt or the like of any size inserted between it and its coacting stationary jaw 2.

It will be observed that the device is of simple, strong and durable construction so that it may be manufactured at a comparatively small cost and its parts will 10 not readily become disarranged or broken.

Having thus described my invention what I claim as new and desire to secure by Letters Patent of the United States, is:—

15. A wrench comprising a stationary jaw having a shank formed at one end with a cylindrical bearing portion and at points intermediate its ends with a stop shoulder and a stationary pawl, a movable jaw having a shank and a loop to surround the shank of the stationary jaw, one wall of 20. said loop being inclined to permit the shank of the mov-

able jaw to rock upon the shank of the stationary one said shank of the movable jaw being provided with a longitudinal series of ratchet teeth to engage said stationary pawl and with a longitudinally extending groove, a leaf spring carried by the shank of the stationary jaw and adapted to enter said groove, a stationary collar surrounding the shanks of both jaws and engaged with the shoulder upon the shank of the stationary one, said collar being adapted to guide the shank of the movable jaw in its sliding and rocking movement, a handle to telescope and rotate upon both of said shanks and formed with a bore having an enlarged upper portion and a reduced lower portion to engage said cylindrical bearing on the shank of the stationary jaw, the enlarged upper portion of the bore of the handle being formed with a cavity or recess to receive 35 the shank of the movable jaw, and means upon the shank of the stationary jaw for retaining said collar and handle upon said shanks, substantially as described.

In testimony whereof I hereunto affix my signature in presence of two witnesses.

MERL H. HARTMAN.
